UNITED STATES PATENT OFFICE.

WILLIAM H. HAWS, OF JOHNSTOWN, PENNSYLVANIA.

COVERING FOR LADLE STOPPER-RODS.

SPECIFICATION forming part of Letters Patent No. 280,618, dated July 3, 1883.

Application filed March 10, 1883. (No model.)

To all whom it may concern:

Be it known that I, WM. H. HAWS, a citizen of the United States, and a resident of Johnstown, in the county of Cambria and State of Pennsylvania, have invented certain new and useful Improvements in Coverings for Ladle Stopper-Rods; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a partial sectional view of this invention. Fig. 2 is an enlarged sectional view. Fig. 3 is a top view of one of the sleeve-bricks. Figs. 4 and 5 are perspective views.

The object of this invention is to provide a sectional covering of improved character for the stopper-rods of furnace-ladles; and the invention consists in the construction and novel arrangement in one end of each sleeve-section of an annular V-shaped groove, the outer wall of which is concave in form, while both walls rise to about the same level, and at the other end of the section an annular V-shaped rib, the outer wall of which is convex, and interior and exterior concentric shoulders extending, respectively, from the base of the rib to the central aperture of the sleeve, and from said base to the external wall thereof, all as hereinafter set forth.

In the accompanying drawings, the letter *a* designates the rod or handle of the ladle-stopper *b*. This rod or handle is covered by slipping upon it the sleeve-sections *cc*, which are designed to engage by their ends the series extending above the surface of the molten metal in the ladle, and being designed to protect the rod from the action of the heated metal.

Heretofore sleeve-sections of fire-clay have been employed to form coverings for the stopper-rods; but such sleeve-sections have been made with a single central projection around the aperture at one end, and a single corresponding central depression of corresponding form and size around the aperture at the other end, and it has been found that the molten metal will find its way through the joint between the sections to the rod.

The sections *cc* of the covering which I have invented are of improved form, and are designed, when put together on the rod, to prevent the access of the molten metal thereto. To this end each sleeve-section has formed in one end an annular groove, *e*, of V shape, the outer wall of which is concave in form, and separated from the aperture *d* of the section by a thick interior wall, *g*, and from the outer surface, *h*, of the section by a thick exterior wall, *l*, these walls rising to equal or nearly equal height. On the other end of the sleeve-section is formed an annular V-shaped rib, *k*, the outer wall of which is convex and corresponding in shape and size to the groove *e*, and adapted to closely fit a groove of similar character formed in the end of the adjacent sleeve-section. From the base of the rib *k* inward to the aperture of the sleeve-section extends an interior shoulder, *m*, and from said base outward extends an exterior shoulder, *n*, and said shoulders are designed to abut against the raised edges of the inner and outer walls, respectively, of the annular groove of the adjacent sleeve-section. In putting these sections, which are made of fire-clay or other refractory material, upon the stopper-rod, a little thinly-mixed fire-clay is poured in the annular groove of each section, and the next section is brought down upon it, making a complete and tight joint. Even should the liquid metal enter the exterior portion of the joint before it could pass down the outer wall of the groove and up the inner wall thereof, it would chill, so that the rod would not be reached.

The walls of converters and other furnaces have been constructed in segmental sections—that is to say, the layers of which the walls are formed have been composed of segmental sections so laid as to break joints—and these sections have been provided with a concavity in the under face, and a bead to fit the concavity in the next layer above on the upper face. These are, however, sectional layers, and do not subserve the purpose designed to be attained by my construction, and are not applicable to ladle stopper-rods. Each section in my construction is complete in itself, and is composed of a single piece so constructed that when the sections are connected as before described, the molten metal cannot reach the rod or handle.

It is obvious that the **V** shape of both the groove and rib insures a close fit between them at the base of the groove, while the respective convex and concave outer walls, as described, 5 serve both to strengthen the joint and furnish large holding-surfaces for the fire-clay cement.

Having described this invention, what I claim, and desire to secure by Letters Patent, is—

10 The sectional sleeve-covering for stopper- rods herein described, wherein the sections are

formed with the **V**-shaped annular groove *c*, concave on its outer wall, and corresponding annular **V**-shaped rib, *k*, convex on its outer wall, substantially as and for the purposes 15 specified.

In testimony whereof I affix my signature in presence of two witnesses.

WILLIAM H. HAWS.
